(57) **CLAIM**

The ornamental design for a composite seal member for semiconductor production apparatus, as shown and described.

DESCRIPTION

1. Composite seal member for semiconductor production apparatus

1.1 : Perspective

1.2 : Front

1.3 : Back

1.4 : Left

1.5 : Right

1.6 : Top

1.7 : Bottom

1.8 : Cross-sectional

1.9 : Partial enlargement of cross-sectional view 1.8

1.10 : Reference

The present article is a composite seal member for semiconductor production apparatuses, such as chemical vapor deposition apparatuses and dry etching apparatuses; as illustrated in the reproduction 1.10, the article is composed of a first component formed of rubber occupying a major part of the article and a second component formed of a synthetic resin, and is to be inserted into the groove of a semiconductor production apparatus; the semiconductor production apparatus itself forms no part of the claimed design; the reproduction 1.8 shows a transverse cross-sectional front view taken along the horizontal center of the reproduction 1.6; and the reproduction 1.9 is an enlarged view showing a left end portion of the cross-sectional view 1.8.

(Continued)

The broken lines shown in Reproduction 1.10 are for the purposes of illustrating environmental structure and form no part of the claimed design.
